G. W. PERKINS.
 ANTICLOGGING ATTACHMENT FOR BUTTON FASTENING MACHINES.
 APPLICATION FILED APR. 2, 1913.

1,080,996.

Patented Dec. 9, 1913.

UNITED STATES PATENT OFFICE.

GEORGE W. PERKINS, OF BOSTON, MASSACHUSETTS, ASSIGNOR TO HEATON-PENINSULAR BUTTON FASTENER COMPANY, OF BOSTON, MASSACHUSETTS, A CORPORATION OF MAINE.

ANTICLOGGING ATTACHMENT FOR BUTTON-FASTENING MACHINES.

1,080,996.

Specification of Letters Patent.

Patented Dec. 9, 1913.

Application filed April 2, 1913. Serial No. 758,298.

To all whom it may concern:

Be it known that I, GEORGE W. PERKINS, citizen of the United States, residing at Boston, county of Suffolk, State of Massachusetts, have invented a certain new and useful Improvement in Anticlogging Attachments for Button-Fastening Machines, of which the following is a specification, reference being had therein to the accompanying drawings.

The invention relates to a button fastening machine. The buttons are usually fed from a hopper through a raceway to the mechanism for attaching the buttons to the boot or shoe or other article to which the buttons are to be attached. When the buttons are delivered from the hopper into the upper end of the raceway they usually fall into the raceway in miscellaneous positions, and it is necessary that they should then be properly positioned so that they will slide down the raceway in proper form, the eye of the button moving down in a groove or slot in the raceway.

The object of the present invention is to provide an improved mechanism for dislodging any buttons which may be piled up in the raceway behind the switch and to prevent clogging of the passage under the switch to the lower raceway.

The invention will be fully understood from the following description taken in connection with the accompanying drawings, and the novel features thereof will be pointed out and clearly defined in the claims at the close of the specification.

For the purpose of fully illustrating the invention it is shown in the accompanying drawings as embodied in a machine by which the wire fasteners are formed as well as attached to the shoe, but it is to be understood that the invention is not limited to use with that particular form of machine.

In the drawings: Figure 1 is a side elevation of a machine embodying the invention. Fig. 2 is a side elevation on an enlarged scale of a portion of the hopper raceway and the anti-clogging attachment. Fig. 3 is a section on line 3-3 of Fig. 1 enlarged. Fig. 4 is a section on line 4-4 of Fig. 1. Fig. 5 is a detail perspective view of the anti-clogging switch detached. Fig. 6 is a detail perspective view of the grooved way for the anti-clogging switch. Fig. 7 is a perspective

view of the anti-clogging switch and the 55 grooved way, shown in Figs. 5 and 6, assembled together.

Referring now to the drawings,—1 represents the hopper in which the buttons are held in bulk, and 2 the hopper stand raceway into which the buttons are delivered by an elevator 3 having the beveled upper edge 4 which lifts the buttons from the hopper and from which they overflow when the elevator has reached the upper end of its stroke 65 and roll over into the raceway 2, the surplus buttons falling back into the hopper 1. The elevator mechanism is operated through a connecting rod 5, crank 6, and driving shaft 7 in a well known manner. From the hopper stand raceway 2 the buttons pass to a raceway 8, which I term the lower raceway of considerably steeper descent than the hopper raceway 2, and the buttons pass down the raceway 8 to the position where the wire 75 for the fastener is to be threaded through the eye of the button. In the particular form of mechanism shown in the drawings it is intended that the wire shall be fed through the eye of the button 9, while the 80 button is positioned in a slot in the top of the arbor 10 and that then the loop and legs of the fastener shall be formed. One form of said mechanism for feeding the wire and forming the fastener is shown and described 85 in Patent No. 982,440, dated January 24, 1911, granted on my application and it is not deemed necessary to show such a mechanism in detail. In the accompanying drawings of the present application a portion of 90 the mechanism for forming the fastener is shown similar to the mechanism shown in said patent. Briefly, 11 is what is termed the former which forms the loop of the fastener and is attached to a former holder 95 12 which is reciprocated by an arm 13 attached to and moved by a lever 14, said arm 13 engaging with a slot 46 in the former holder 12. Said lever 14 is fulcrumed on a pivot 15, the rear arm of said lever 14 carrying a roll which engages with a cam groove 16 in the side of cam 17 which is mounted on shaft 7. The legs of the fastener are formed by what I term a slide 18 which is actuated by an arm 19 attached to and carried by a lever 20, said arm 19 engaging with a slot 21 in the slide 18. Said lever 20 is fulcrumed at 22, the rear arm of said lever

carrying a roll which engages with a cam groove 23 in the opposite face of the cam 17 from that which contains the cam groove 16. These cam grooves 16 and 23 are so formed that the former 11 and slide 18 are actuated at the proper periods of time in the movement of the machine to form the loop and legs of the fastener. The details of a form of construction for actuating said former 10 and slide at the proper times are fully described in said Patent No. 982,440.

When the button is in position for receiving the wire for the fastener, as shown in Fig. 1, means should be provided for holding the button against movement during the feeding of the wire and forming of the fastener, and this clamping means should also be controlled as to its time of movement suitably with relation to the time of movement of the fastener forming mechanism. The details of this clamping or placer mechanism, as it is termed, do not form a part of the present invention, being fully shown and described in another application 20 by me. Briefly, it consists of a placer block 24 suitably connected with a lever 25 which is controlled by the movement of the former holder 12. Mechanism for carrying the lowermost button in the raceway and properly positioning it beneath the placer to receive the wire is actuated by a rod 26 pivotally connected with one end of a lever 27, said lever 27 being fulcrumed at 28 to the frame of the machine, the rear arm of said 30 lever 27 carrying a roll which engages with the rim of said cam 17 so that its movements will be properly timed with reference to the movement of the fastener forming mechanism. The particular details of the mechanism connected with the rod 26 which engage and carry the button beneath the placer are not shown herein, as they form the subject of another application.

The anti-clogging attachment which forms 45 the special subject of the present application will now be described.

Secured to the frame just above the hopper stand raceway near its lower end is a block 29 which serves as a holder and guide 50 for the anti-clogging switch block. This guide block 29 is adjustably secured in proper relation to the hopper raceway by means of a screw 30 which extends vertically down through a tapped-out hole in a 55 lug 31 on the frame of the machine above the hopper raceway and down into a tapped-out hole 32 in the holder block 29. In order to aid the screw 30 to hold the block 29 steady, I provide screws 47, 47 which pass 60 through slots 48 in the hopper guard wall 39 into tapped-out holes 49 in the side of the block 29. These slots 48 are elongated to permit adjustment of the block 29 to a different elevation. Said holder block 29 is formed 65 with a groove 33 in the side thereof, in which

is slidably mounted the anti-clogging switch. The holder block 29 lies above the hopper raceway in a plane which is at the same inclination as the plane of the raceway. The upper end 34 of the holder block 29 forms an acute angle with the grooved side of said holder block 29 so that said upper end of the holder block extends in a diagonal direction crosswise of the hopper raceway at some elevation above the raceway. The switch is 70 formed with a shank 35 which is slidably mounted in the groove 33 in the side of the holder block 29 and is formed with a head 36 which is inclined with relation to the shank 35 the same as the inclined end 34 of the holder block 29 is inclined to the grooved side of said block, so that the face of said head 36 which is toward the holder block will lie against said inclined face of the holder block when it is in its downward position. Preferably the said switch is provided with a face plate 36^a of hard steel while the body 36^b may be made of less expensive material. (See Fig. 3.)

Projecting from one side of the shank 35 of the switch is a stud 37 which extends laterally through an elongated slot 38 in the guard wall 39 rising from the side of the hopper raceway and said stud 37 engages with a vertical elongated slot 40 in the upper 95 end of a lever 41 fulcrumed at 42 to the frame of the machine, the lower arm of said lever 41 being formed with an elongated slot 43 with which there engages a stud 44 which projects from one side of the former actuating lever 14 so that said lever 41 will be actuated by the same lever which actuates the former 13 and its movement will be timed thereby. When the former actuating lever 14 moves on its upward stroke after having 100 formed the loop of the fastener the lever 41 will be rocked on its fulcrum thereby moving the switch 36 on its down stroke in the grooved hollow block 29 and when the lever 14 moves in a direction to carry the former 105 down to form the loop of the fastener the lever 41 will be rocked in the reverse direction carrying the switch 36 on its up stroke. The switch 36, as previously stated, lies 110 diagonally crosswise sufficiently above the hopper raceway, as shown in Fig. 1, so that when the buttons are properly seated in the raceway they will easily slide down under the switch. If there are any of the buttons in an inverted position on the raceway so 115 that the eyes stick up or if there is a pile of buttons, one above another, they will engage the diagonal face of the switch 36 as the switch 36 makes a reciprocation up and back at each complete stroke of the former and slide. This frequent movement or vibration 120 of the switch will throw the buttons to one side and off of the hopper raceway on the opposite side from the wall 39, the top of the raceway being open on that side.

The screw 30 which engages and suspends the holder block 29 over the raceway is provided with a finger piece or head 45 to manipulate the screw. The screw is formed 5 with a collar 50 on the under side of the lug 31 and the head or thumb piece 45 is made fast to the shank of the screw so that when the screw is turned it will raise or lower the block 29. By turning the screw 10 it may be raised or lowered and the holder plate 29 together with the switch 36 will thereby be raised or lowered so that it may be adjusted to different elevations above the hopper raceway to allow for varying sizes 15 of buttons. The vertically elongated slot 40 in the lever 41 will accommodate this adjustment of the switch.

While the invention has been shown as embodied in a machine in which the actuating lever 41 for reciprocating the switch is itself actuated by the mechanism which forms and carries the fasteners, it is obvious that the lever 41 may be actuated by independent mechanism. It is also obvious 25 that the switch may be reciprocated through other means than a lever such as 41.

What I claim is:

1. In combination with a button raceway, a clearance switch above the raceway movable in a path parallel with the runway for the buttons in the raceway and over the 30 heads of the buttons properly seated in the raceway, said switch member being formed with its upper end extending across the width of the raceway and beveled at an angle 35 diagonally with the line of movement of the buttons in the raceway, and means for reciprocating said switch member in a path parallel with and above the path of movement of the buttons properly seated in the raceway.

2. In combination with a button raceway, a switch block holder, means for holding said switch block holder above the raceway, 45 said switch block holder being formed with a guideway parallel with the line of movement of the buttons in the raceway, a switch block having a shank which is seated in said guideway and slidably therein, said switch 50 block having a head which extends transversely above said raceway at the upper end of said holder block, and means for reciprocating said switch in a path parallel with the line of movement of the buttons in the raceway and at an elevation slightly above 55 said raceway.

3. In combination with a button raceway, a clearance switch above the raceway movable in a path parallel with and above the 60 upper surface of the raceway, said switch member being formed with its upper end

beveled at an angle diagonally with the line of movement of the buttons in the raceway, means for reciprocating said switch member in a path parallel with and above 65 the path of movement of the buttons properly seated in the raceway, means for positioning a button at the foot of the raceway to receive a fastener, means for forming a fastener, and means for actuating the forming and positioning mechanism and for reciprocating said switch member whereby their movements are timed with relation to each other.

4. In combination with a button raceway, 70 a clearance switch above the raceway movable in a path parallel with and above the upper surface of the raceway, said switch member being formed with its upper end beveled at an angle diagonally with the line 75 of movement of the buttons in the raceway, one side of said raceway being open and the other side being formed with a side wall rising above the raceway, said side wall being formed with an elongated slot, said 80 switch member being formed with a stud which projects through the slot in the side of said wall, a fulcrumed lever which engages with said stud, and means for rocking 85 said lever on its fulcrum whereby reciprocating movement is given to said switch member.

5. In combination with a button raceway, a stationary switch holder mounted over the raceway, a clearance switch slidably mounted 90 on said holder, having its upper end diagonally inclined crosswise of the raceway at a slight elevation above the raceway, and means for reciprocating said clearance 95 switch in a path above said raceway and 100 parallel with the path of movement of the buttons in the raceway.

6. In combination with a button raceway, a switch block holder, adjustable means for holding said switch block holder above the 105 raceway, said switch block holder being formed with a groove in one side thereof parallel with the raceway, a switch block having a shank which is seated in said groove and slidably therein, said switch 110 block having a head which extends transversely above said raceway at the upper end of said holder block, and means for reciprocating said switch in a path parallel with and at an elevation slightly above said raceway.

In testimony whereof I affix my signature, in presence of two witnesses.

GEORGE W. PERKINS.
